UNITED STATES PATENT OFFICE.

FREDERICK L. KANE, OF HUNTINGTON, NEW YORK.

PLASTER-SUPPORT FOR WALLS.

1,121,017.

Specification of Letters Patent.

Patented Dec. 15, 1914.

Application filed May 18, 1912. Serial No. 698,652.

To all whom it may concern:

Be it known that I, FREDERICK L. KANE, of Huntington, Suffolk county, New York, have invented a new and useful Improvement in Plaster-Supports for Walls, of which the following is a full, clear, and exact description.

My invention relates to improvements to plaster supports for walls of buildings, and 10 this particular invention is an improvement on the invention disclosed in Letters Patent of the United States No. 1,003,754, dated September 19, 1911.

The object of my present invention is 15 to minimize the transverse flexibility of the stiffening strip or rib, so as to stiffen the plaster support transversely without the use of additional material and without additional expense, by simply crimping the 20 stiffening strip or rib longitudinally. In my previous patent above referred to, I disclose a flat strengthening strip which is applied at intervals transversely to a sheet of paper either laminated or plain, so that 25 when the plaster support is applied to the studding or ceiling beams of a wall, the strip will prevent the paper or fibrous material from sagging before the plaster sets. This structure works satisfactorily if 30 intelligently applied, and care is taken to have the board stretched flat and taut before it is nailed to the studding or wall of a room, but where the material is sent out to the trade and applied by workmen of various 35 orders of intelligence, it sometimes happens that the workman will be careless in applying the board or sheet, and owing to its great flexibility it will bend of its own weight, and the workman will nail the sheet 40 support to the wall without taking pains to straighten it out, and thus a curve or bulging in the sheet is produced, making it more difficult to produce a flat satisfactory wall when the plaster is applied, and also 45 making it necessary to use more plaster to fill up the irregularities. I have found by experimenting that if the transverse strengthening strips or ribs which are applied to the sheet, are crimped longitudinally, either by a single curve, or by a plurality of corrugations, the strip or rib is 50 very much strengthened without increasing the thickness of the material, and it can be as easily applied to the plaster sheet which 55 is to be stiffened. When the strengthening strip is stiffened as described, it makes the supporting sheet cost no more, it is applied transversely as in the other patent referred to so that the sheet can be rolled up as well as heretofore and when applied, the rib is 60 sufficiently rigid to hold the plaster sheet taut so that when nailed to the wall or studding it will be perfectly flat, no matter how green or unintelligent the workman may be who applies it. This will be clearly understood from the description which follows.

Reference is to be had to the accompanying drawings forming a part of this specification, in which similar reference characters indicate corresponding parts in all the views.

Figure 1 is a broken front elevation showing the application of the plaster support to the studding of a room. Fig. 2 is a broken 75 enlarged perspective view showing a portion of the paper sheet with the stiffening strips thereon, and Figs. 3 to 6 are details of various forms of the strengthening strip. The support comprises a sheet 10 which is 80 of flexible material so that it can be rolled up conveniently and shipped in a roll, and it is usually of a width to span two joists 11 when these are placed at ordinary distances. The transverse strips 12 are of thin 85 sheet metal so as to give additional strength to the sheet 10, and they are applied transversely at frequent intervals, the mode of application being immaterial, but they are preferably provided with struck-up brads 90 which pierce the sheet 10 and are clenched as described in the former patent, and as indicated at 14. When the strip 12 is perfectly flat, it has the necessary strengthening effect if the sheet 10 is carefully applied as above described, but owing to the great flexibility of the sheet, and of the strip 12, sagging may occur through carelessness. I find, however, that by making the transverse strengthening strip in a 95 curved form, as shown in Fig. 3, all this sagging tendency is done away with, and the strip is stiff enough to hold the sheet 10 taut and flat when applied either overhead or to a side wall.

The strengthening devices need not be any thicker than heretofore, and it costs no more to apply it because it is applied by machinery, and the machine which applies the strip can shape it as it is applied, without any additional expense. Obviously the strip can be strengthened, that is stiffened,

by curving or corrugating it longitudinally, in a great many ways. For instance, by a simple curve as shown in Fig. 2; by having the curved strip provided with flanges 13 5 as in Fig. 3; by simply giving the strip a single sharp corrugation as at 15 in Fig. 4; by giving it a plurality of parallel or essentially parallel corrugations as at 16 in Fig. 5, or by a plurality of less sharp corrugations as shown at 17 in Fig. 6. Doubtless 10 the strip might be similarly stiffened by imparting other forms to it, but the essential thing is to have it crimped or corrugated longitudinally as stated, to the end that the 15 handling of the sheet may not be interfered with, but that it will keep the sheet 10 straight when the latter is applied.

I have not disclosed any particular structure of the sheet 10, as this can be a sheet of 20 paper, plain or laminated, or of other fibrous

flexible material which will afford a suitable support for wall plaster when the latter is applied to the sheet. It will be understood, as in the previous case above referred to, that the sheet is used as a substitute for 25 lath, and that it is nailed to the studding or wall in the usual way, after which the plaster and skim coat are applied as usual.

I claim:—

As an improved article of manufacture, 30 a flexible sheet of fibrous material for a plaster wall support, said sheet having on its surface thin, transverse metallic strengthening strips which are firmly secured to the sheet, and which are transversely curved or 35 corrugated.

FREDERICK L. KANE.
